UNITED STATES PATENT OFFICE.

CHARLES L. PEIRCE, JR., OF PITTSBURGH, PENNSYLVANIA.

METHOD OF MAKING INSULATOR SUPPORTS.

Application filed July 16, 1926. Serial No. 122,826.

This invention relates to insulator supports and more particularly to the type known as secondary racks such as are commonly used for mounting a row of insulators upon a supporting wall, pole or the like.

Supports of this type generally consist of a base section, by means of which the device is secured to the supporting structure and which has mounted thereon a plurality of separately formed outwardly extending insulator supporting arms, the latter being of a configuration dependent upon the particular type of insulator to be supported.

It has heretofore been customary to form the arms separately and secure them to the base section, which itself is usually formed by one or more parts, by any suitable manner of fastening such, for example, as riveting.

It is apparent that this form of construction is subject to serious defects from the commercial viewpoint; there being, among others, the cost and time of manufacturing, due to the necessity of assembling the various parts and fastening them securely together. In addition, the strength of such devices is always largely dependent upon the strength of the particular fastening means employed rather than upon the design and construction of the completed rack.

An object of this invention is to provide an improved method of manufacturing insulator supports of the type set forth.

A further object is to provide a method of manufacturing insulator supports more rapidly and cheaply than has heretofore believed to have been possible.

A still further object is to provide a method of manufacturing insulator supports from sheet metal with practically no waste of the stock.

A still further object is to provide an insulator support of simple and rugged construction which will be cheap and easy to manufacture and which will overcome disadvantages encountered in prior art structures known to me.

These and other objects which will be apparent to those skilled in this particular art are accomplished by means of the present invention, one embodiment of which is illustrated in the accompanying drawings, in which Figure 1 is a plan view of a piece of sheet metal stock showing a method of stamping one form of blanks therefrom. Fig. 2 is a side elevation of an insulator rack made

from the form of blank shown in Fig. 1. Fig. 3 is a sectional view on the line 3—3 of Fig. 2 showing one of the insulator supporting arms in plan. Fig. 4 is a view similar to Fig. 1 illustrating the application of the invention to the manufacture of a different type of insulator rack. Fig. 5 is a side elevational view of a rack formed from the blanks illustrated in Fig. 4. Fig. 6 is a front view thereof. Fig. 7 is a sectional view on the line 7—7 of Fig. 5. Fig. 8 is a similar view on the line 8—8 thereof and Figs. 9 and 10 are views similar to Figs. 2 and 3, illustrating a different form of securing means.

It will be apparent from the following description that the present invention is applicable to the manufacture of various forms of insulator supports although the accompanying drawings illustrate its application to two forms of secondary racks only.

One of the commercial advantages resulting from the present invention is the manufacture of articles of this type with practically no waste whatever of the stock from which they are made.

As illustrated, the invention contemplates the severing of a sheet of flat metal stock in such manner that two blanks are simultaneously formed which are capable of being employed together in the formation of apparatus of the kind herein described. The method further contemplates the formation of one of said blanks from the portion of the stock which, in an ordinary stamping operation, would be waste material in so far as concerns the formation of the other blank.

In the preferred embodiment two blanks are cut from a single strip of stock in such manner that the base portions of the blanks are formed from material adjacent the opposed longitudinal edge of the strip, and the arm portions, from which the insulator supporting arms are eventually formed, project inwardly and in such relation that the arms of one blank extend in the opposite direction to and interlock with the arms of the other blank.

In the specific embodiment illustrated each blank comprises a longitudinal section which is adapted to become a part of the base section of the finished rack. Those portions of the blanks which ultimately become the insulator supporting arms, namely, the arm blanks, are formed by the line of severance between the two opposed blanks. It will thus

be seen that the material forming the arm of one blank interlocks with, and fits between the corresponding parts of the opposed blank so that there will be practically no waste of 5 stock.

It will be apparent that with some configurations of blank arms it may be desirable, to so sever the stock as to produce some waste, but my invention broadly contemplates 10 the formation of the opposed blanks so as to minimize waste and labor, and this may be accomplished by cutting the blanks from the stock so that they are simultaneously formed in opposed relation with portions of one 15 blank interleaving with portions of the other blank.

After the blanks are cut the longitudinal section is flanged and the material of the arms is bent to provide two complementary 20 blanks which can be joined, preferably by butt welding to form a finished rack.

In the illustrated embodiment of this invention a strip of sheet metal stock 10 is first 25 cut along a line 11 of irregular contour to provide blank strips each of which has a longitudinal section 12 and outwardly extending separated sections or arms 13 formed by the interlocking sections of the complementary blanks which will result from the 30 irregular contour of the line 11 along which the stock is cut. It will be seen that cutting the stock along such a line to form a number of duplicate blank strips practically eliminates any waste whatever. Each blank strip 35 is then severed along lines 14 to provide duplicate rack blanks of suitable length. Of course, the blanks can be formed by cutting along the lines 14 at the same time that the strip is cut along the irregular line 11. This 40 entire operation can be conveniently performed by stamping.

In manufacturing the form of secondary rack illustrated in Figs. 1 to 3, the arm blanks 13 are of the slightly tapering contour illustrated and their outer ends are cut to form notches 15 in each side thereon resulting in each arm blank being made up of a tapering relatively wide section 16 and a projecting narrow end or nose 17. The 50 notches 15 are also preferably stamped out at the time the blank is formed from the flat stock.

After a blank is cut as described, the edges of the wide portions 16 of each arm are bent 55 along the dotted lines 17, see Fig. 1, so as to provide angularly extending surfaces 18, see Fig. 3; and the narrow nose 17' of each arm is bent into a substantially semi-cylindrical finger 19. The longitudinal section 60 12 of each blank is bent along the dotted line 20 to form a flange 21 and it will be noted that while the flange extends in one direction upon one blank end the surfaces 18 and fingers 19 extend in the opposite direction upon 65 the same blank, another complementary

blank is formed by bending its flange 21, surface 18 and finger 19 in the opposite direction relatively to the corresponding parts of its complementary blank. Two complementary blanks are then united by welding the 70 meeting edges of the surfaces 18 and of the fingers 19, see Fig. 3, so that a secondary rack 22 having spaced insulator supporting arms 23 and a base section 24 is provided.

In addition to welding two complementary blanks together the nose 17' of each arm may be provided with a perforated lug 35 which is riveted to the corresponding lug of the associated complementary blank. A spacer 36 is positioned between the sides of 80 the arms adjacent the base flanges and provides an additional means for securing them together and also constitutes a reinforcement for each arm at that portion subject to the greatest buckling strains. It will be apparent that it is unnecessary to weld the parts together when the latter method of fastening is employed.

It will be noted that the notches 15, as a result of the bending to which the metal of 90 the arms has been subjected, provide openings 25 in the outer end of each arm of the finished rack through which the usual pin on which the insulators are mounted can be threaded through the arms for holding the 95 insulators in position thereon. Each flange 21 forming the base 24 is provided with slots 26 which may conveniently be formed at the time the metal stock is stamped.

In manufacturing this type of secondary 100 rack in accordance with the present invention, it will be noted that the only waste material is the material which is cut from the original stock to form the notches 15 and slots 26.

The invention is also applicable to the manufacture of other forms of insulator supports such, for example, as the type of racks used for mounting pin type insulators, illustrated in Figs. 4 to 8. In this case the irregular line 11 along which the metal stock is cut will have a contour of the proper configuration to form the arms 13 of substantial L-shape as illustrated. The blanks are provided preferably by stamping in the same 110 manner as heretofore described. After each blank is cut the edges of the arms are bent along the dotted lines 27 with the result that the upper ends of the arms are semi-cylindrical as shown in Fig. 8 while their lower 120 ends adjacent the base sections are more rectangular in outline. The longitudinal section of each blank is bent along the line 28 to form a flange 29 and the angularly extending surfaces 30 of complementary 125 blanks are united by butt welding the bent edges of the arms to provide a finished blank having a base section 31 formed by the flanges 29 on which are supported the integral insulator supporting arms 32 formed 130

by joining the two half sections of complementary blanks. The flanges 29 have notches 33 for mounting the rack upon a support.

It will be seen that the only waste of stock 5 material in the manufacture of the rack illustrated in Figs. 4 to 8 is that which is formed by cutting the notches 33.

Although I have illustrated a particular series of steps for manufacturing two examples of insulator supports, it will be obvious 10 that various changes, omissions, additions and substitutions may be made therein without departing from the spirit of this invention and that the invention is not limited to details herein set forth except as 15 specified by the appended claims.

What I claim as new and desire to secure by Letters Patent is:

1. The method of manufacturing insulator 20 supports which consists in forming separate complementary blanks from a single piece of stock and joining said blanks to form said support.

2. The method of manufacturing insulator 25 supports which consists in cutting a plurality of blanks, each having a longitudinal section provided with outwardly extending arms and joining said blanks to form a rack having a base with integral insulator supporting 30 arms extending outwardly therefrom.

3. The method of manufacturing insulator supports which consists in forming a plurality of blanks, each having a longitudinal section provided with outwardly extending arms 35 and joining the edges of said arms so as to form a secondary rack having spaced base members with integral insulator supporting arms extending outwardly therefrom.

4. The method of manufacturing insulator 40 supports which consists in forming duplicate blanks having longitudinal sections provided with outwardly projecting arms from interlocking sections of flat stock, bending the edges of said arms, flanging the longitudinal 45 sections and securing the bent edges of the arms of one blank to the bent edges of the arms of the other blank with the flanges of said longitudinal sections positioned adjacent each other to form an insulator supporting rack.

5. The method of manufacturing insulator 50 supports which consists in providing a flat sheet of material, stamping duplicate blanks having longitudinal base sections and projecting arms from interlocking portions of

said sheet, bending said blanks and securing 55 said blanks together to form a supporting rack.

6. The method of manufacturing insulator supporting racks which consists in providing a strip of flat stock, cutting said stock so that 60 the edges of the stock form longitudinal sections of duplicate blanks and the interlocking central sections of said stock form arms projecting outwardly from each of said longitudinal sections, and joining two of said blanks 65 to form a secondary rack.

7. The method of manufacturing a secondary rack having a base provided with integral insulator supporting arms which consists in cutting a strip of sheet metal along an irregular line so as to form duplicate blanks having 70 longitudinal sections and outwardly extending arms, notching the corners of said arms to provide a relatively narrow nose, forming complementary blanks by flanging the longitudinal sections, bending the edges of said arms and the end of said nose to extend angularly therefrom, and butt welding the bent edges of said arms to the similar bent edges of 75 a complementary blank.

8. The method of manufacturing a secondary rack having a base provided with integral insulator supporting arms which consists in cutting a strip of sheet metal along an irregular line so as to form duplicate blanks 80 having longitudinal sections and outwardly extending arms, notching the corners of said arms to provide a relatively narrow nose, forming complementary blanks by bending the edges of said arms and the end of said 85 nose to extend angularly therefrom, and butt welding the bent edges of said arms to the similar bent edges of a complementary blank.

9. The method of manufacturing a secondary rack having a base provided with integral 90 insulator supporting arms which consists in cutting a strip of sheet metal along an irregular line so as to form duplicate blanks having longitudinal sections and outwardly extending arms, flanging the longitudinal section of 95 said blanks, bending the edges of said arms so as to form a semi-cylindrical end and a substantially rectangular section adjacent the base and uniting the bent edges of the arms of two complementary blanks by butt welding.

In testimony whereof, I have hereunto subscribed my name this 26th day of June, 1926.

CHARLES L. PEIRCE, JR.
